DESK NOVELTY LETTER HOLDER

Walter W. McGuire, Jackson, Mich.

Application June 12, 1946, Serial No. 676,210

1 Claim. (Cl. 120—82)

1

My invention relates to a device for holding letters, papers, and the like.

An important object of the invention is to provide a novel letter holder for use upon a desk, or the like, the letter holder also forming a novel and attractive desk ornament.

A further object is to provide a letter holder including gravity actuated self-adjusting means for securing a number of letters in place.

A still further object of the invention is to provide a device of the above mentioned class which is extremely simple, and therefore inexpensive to manufacture.

Other objects and advantages of the invention will be apparent during the course of the following description.

In the accompanying drawings, forming a part of this application, and in which like numerals are employed to designate like parts throughout the same,

Figure 1 is a perspective view of a letter holder embodying the invention,

Figure 2 is a plan view of the same,

Figure 3 is a central vertical longitudinal section taken on line 3—3 of Figure 2,

Figure 4 is a side elevation of a knob removed, part in section, and,

Figure 5 is a side elevation of a pin removed.

In the drawings, where for the purpose of illustration is shown a preferred embodiment of the invention, the numeral 10 designates a generally flat rectangular base, provided in its upper surface with a central longitudinal groove or recess 11, the bottom 12 of which slopes downwardly toward one end of the base 10, from a point on the top surface of the base, near the opposite end of the same. The recess 11 is parallel to the sides of base 10, as shown. Side upstanding portions or guide shoulders 13 are formed by the recess 11. A vertical rectangular end or wall 14 is permanently rigidly secured to one end of base 10, as shown, and projects above the same for a substantial distance. This end 14 extends for the full width of base 10, and its sides are flush with the sides of the base.

A removable weight or roller 15 is arranged in the recess 11, and is adapted to roll freely upon the inclined bottom 12. The axial width of roller 15 is slightly less than the width of recess 11, and the roller is guided by the inner sides 16 of shoulders 13. The roller 15 is cylindrical, and provided upon its opposite sides and at its center with knobs or handles 17, having axial openings 18 to receive dowel pins 19, or the like, which also engage in an axial opening 20 extending through the center of roller 15.

The parts of the device above described may be formed of wood, metal, plastic, or any other suitable material. Suitable ornamentation may be provided, and I have shown inlay strips 21 arranged in the top surface of base 10, and simi-

2

lar inlay strips 22 in the inner vertical surface of end 14. These strips 21 and 22 may be made any color desired, such as red.

In use, the device is placed upon a desk, or the like, as in Figure 1. The roller 15 will always tend to roll down the inclined bottom 12, and will therefore exert a constant force against the inner surface of end 14. The desired number of letters or papers may be placed vertically between the end 14 and roller 15, and will be held in place by the roller. As each letter or paper is withdrawn, the roller 15 will automatically roll down the bottom 12 a slight distance, due to gravity, and the remaining letters will be held in place. The knobs 17 facilitate handling the roller 15, which is removable.

It is to be understood that the form of the invention herewith shown and described is to be taken as a preferred example of the same, and that various changes in the shape, size and arrangement of parts may be resorted to, without departing from the spirit of the invention, or the scope of the subjoined claim.

I claim:

25 A device for holding letters and the like, comprising a substantially horizontal generally flat rectangular low base provided upon its upper surface with a longitudinal shallow recess extending for substantially its entire length, the bottom 30 of said shallow recess being inclined downwardly toward one end of said base, spaced parallel longitudinal guide shoulders at the sides of the base and having inner vertical edges formed by said shallow recess, a substantially vertical end wall 35 secured to the base at its end adjacent to the lowermost end of the inclined bottom and extending transversely across the base and above the base for a substantial distance, and a removable cylindrical roller disposed within the 40 recess and adapted to roll upon said bottom and having its ends guided by said inner vertical edges, the roller tending to engage the inner side of said end wall and serving to removably clamp letters and the like against the same.

WALTER W. MCGUIRE.
